[57] CLAIM

The ornamental design for a refuse bin grabber, as shown and described.

DESCRIPTION

FIG. 1 is a top perspective view of a refuse bin grabber in accordance with my new design;

FIG. 2 is a side elevational view thereof; the opposite side being a mirror image thereof;

FIG. 3 is a front elevational view thereof;

FIG. 4 is a top plan view thereof;

FIG. 5 is a rear elevation view thereof; and,

FIG. 6 is a bottom plan view.

The broken line showing of environment in FIG. 2 is for illustrative purposes and forms no part of the claim design.
